United States Patent Office

Des. 215,505
Patented Sept. 30, 1969

215,505

MOTORIZED SURFBOARD

Bernard C. Tierney, Hopkins, Minn., assignor to Leisure Industries, Edina, Minn., a corporation of Minnesota

Filed Aug. 21, 1968, Ser. No. 13,217

Term of patent 14 years

Int. Cl. D21—03

U.S. Cl. D71—1

FIG 1

FIG 2

FIG 3

FIG 4

FIG 5

FIGURE 1 is a plan view of a motorized surfboard showing my new design;

FIGURE 2 is a right elevation view of the same, the left elevation view being a mirror image;

FIGURE 3 is a front elevation view of the same;

FIGURE 4 is a rear elevation view of the same; and

FIGURE 5 is a bottom view of the same.

I claim:

The ornamental design of a motorized surfboard, as shown and described.
